The ornamental design for a recycling bin, as shown and described.

DESCRIPTION

FIG. 1 is a perspective view of a first embodiment of my recycling bin.

FIG. 2 is a front view thereof.

FIG. 3 is a back view thereof.

FIG. 4 is a side view thereof, the left and right side views are mirror images.

FIG. 5 is a top view thereof.

FIG. 6 is a bottom view thereof.

FIG. 7 is a perspective view of a second embodiment of my recycling bin, the top and bottom views of the second embodiment are identical to the top and bottom views of the first embodiment.

FIG. 8 is a front view thereof.

FIG. 9 is a back view thereof.

FIG. 10 is a side view thereof, the left and right side views are mirror images.

FIG. 11 is a perspective view of a third embodiment of my recycling bin, the top and bottom views of the third embodiment are identical to the top and bottom views of the first embodiment.

FIG. 12 is a front view thereof.

FIG. 13 is a back view thereof; and,

FIG. 14 is a side view thereof, the left and right side views are mirror images.
